UNITED STATES PATENT OFFICE.

ARTHUR C. HOPKINS, OF NILES, MICHIGAN, ASSIGNOR TO NATIONAL STANDARD COMPANY, OF NILES, MICHIGAN.

LIFTING JACK.

Application filed March 26, 1927. Serial No. 178,588.

The main object of this invention is to provide an improved lifting jack of the screw type which is very compact when collapsed and of considerable height when fully extended, and one in which the parts are so arranged that they may be easily extended and collapsed.

Objects pertaining to details and economies of the invention will definitely appear from the detailed description to follow.

The invention is defined in the claims.

A structure embodying the features of my invention is clearly illustrated in the accompanying drawing forming a part of this application, in which:

Fig. 1 is a side elevation of a structure embodying the features of my invention.

Fig. 2 is a detail view mainly in vertical section on line 2—2 of Fig. 1.

Fig. 3 is a horizontal section on a line corresponding to line 3—3 of Figs. 1, 2 and 5.

Fig. 4 is a detail view mainly in horizontal section on line 4—4 of Figs. 1, 2 and 5.

Fig. 5 is a diagrammatic view showing the spiral control groove of the standard extended.

In the embodiment illustrated my improved jack comprises a standard 1 provided with a suitable base 2. The standard 1 has a longitudinal bore 3 therein with a spiral groove 4 extending from end to end thereof, this groove terminating in horizontal extensions 5, the outer or end walls 6 of which are beveled or inclined.

The tubular lifting member 7 is adapted to telescope in the bore 3 and is externally threaded. The standard 1 is provided with a yoke-like bracket 8 at its upper end which has an opening 9 alined with the bore of the standard. The nut 10 has threaded engagement with the member 7 and is supported on the end of the standard by the thrust bearing 11. This nut has a beveled gear 12 with which the driving gear 13 meshes, this driving gear being mounted on the bracket 8 and having a hub adapted to receive the handle 14 by means of which the gear 13 is rotated.

As the lifting member 7 is raised and lowered by the rotation of the nut it is rotated within the standard by means of the pin 15 engaging the spiral groove 4. This pin is arranged in a radially disposed holder 16, a coiled spring 17 yieldingly supporting the

When the lifting member is raised or lowered to bring the pin 15 into the horizontal plane of the groove extensions 5 the member 7 may be rotated in one direction with the nut as a unit, the pin constituting a stop limiting the upward travel of the lifting member, while the split ring 18 on the upper end of the lifting member 7 constitutes a stop limiting the downward travel of the lifting member.

The second lifting member 19 has threaded engagement with the lifting member 7, the member 19 having a head 20 to engage the work. With the parts thus arranged the lifting member 7 is positively rotated during its upward and downward travel, thereby preventing "setting" of these parts; that is, there is a positive differential movement and the friction is very materially reduced.

When the lifting member 7 is at the ends of its stroke the pin 15 readily passes up the inclined walls 6 of the groove, allowing rotation of the nut and lifting member as a unit in one direction. However, as soon as this rotation is reversed the pin engages the spiral wall 21 of the groove opposite the inclined end 6, guiding the pin into the groove and controlling the rotation of the lifting member 7 throughout its travel. The lifting member 19 is free to rotate until its head 20 engages the work and, it being held against rotation, the member 7 acts as a driving nut for the member 19.

My improved lifting jack is very simple and economical in structure, and at the same time is durable and easy to operate.

Having thus described my invention what I claim as new and desire to secure by Letters Patent is:

1. In a lifting jack, the combination of a standard having a longitudinal bore with an internal spiral groove therein terminating at its ends in oppositely disposed horizontal extensions having beveled end walls, said standard being provided with a yoke-like bracket having a part disposed in spaced relation to the upper end of the standard with an opening therein alined with said bore, a nut interposed between said bracket and standard and provided with a gear, a thrust bearing disposed between the nut and the end of the standard, a driving gear mounted on said bracket coacting with said gear on said nut, a tubular lifting member disposed in said standard and externally

threaded to coat with said nut, a stop on the upper end of said lifting member coacting with the bracket to limit its downward travel, a yieldingly supported pin disposed radially in said lifting member and coacting with said spiral groove to rotate said lifting member during its longitudinal travel under the action of said nut and yielding to permit the rotation of said lifting member and nut as a unit in one direction when the pin is in the horizontal plane of one of said groove extensions, and a second lifting member disposed within and having threaded engagement with said tubular lifting member and provided with a head.

2. In a lifting jack, the combination of a standard having a longitudinal bore with an internal spiral groove therein terminating at its ends in oppositely disposed horizontal extensions having beveled end walls, a driven nut mounted on the upper end of said standard, a tubular lifting member disposed in said standard and externally threaded to coat with said nut, a stop on the upper end of said lifting member coacting with the bracket to limit its downward travel, a yieldingly supported pin disposed radially in said lifting member and coacting with said spiral groove to rotate said lifting member during its longitudinal travel under the action of said nut and yielding to per-

mit the rotation of said lifting member and nut as a unit in one direction when the pin is in the horizontal plane of one of said groove extensions, and a second lifting member disposed within and having threaded engagement with said tubular lifting member and provided with a head.

3. In a lifting jack, the combination of a standard having a longitudinal bore with an internal spiral groove therein, a nut rotatably mounted on said standard and provided with a gear, a driving gear mounted on said standard coacting with said gear on said nut, a tubular lifting member disposed in said standard and externally threaded to coat with said nut, a yieldingly supported pin disposed radially in said lifting member and coacting with said spiral groove to rotate said lifting member during its longitudinal travel under the action of said nut and yielding to permit the rotation of said lifting member and nut as a unit in one direction when the pin is in the horizontal planes of the ends of said groove, and a second lifting member disposed within and having threaded engagement with said tubular lifting member and provided with a head.

In witness whereof I have hereunto set my hand.

ARTHUR C. HOPKINS.
